DESIGN FOR A TABLE

Francis Frederick Kallstrom and Thaddeus Leon
Euclid Haug, Berkeley, Calif.

Application January 9, 1933. Serial No. 46,932

Term of patent 14 years

To all whom it may concern:

Be it known that we, FRANCIS F. KALLSTROM and THADDEUS L. E. HAUG, citizens of the United States, residing at Berkeley, in the county of Alameda and State of California, have invented a new, original, and ornamental Design for a Table, of which the following is a specification, reference being had to the accompanying drawing, forming part thereof.

Fig. 1 is a top perspective view of the table of our new design; and

Fig. 2 is a bottom perspective view thereof.

We claim:

The ornamental design for a table, as shown. In testimony whereof we have hereunto set our hands.

FRANCIS FREDERICK KALLSTROM.
THADDEUS LEON EUCLID HAUG.
